Design

C

PATENTED
JUN 15 1869

United States Patent Office.

ISAAC N. ROSS, OF HOLDEN, MASSACHUSETTS, ASSIGNOR TO
EARLE STOVE COMPANY.

Design No. 3,552, dated June 15, 1869.

DESIGN FOR A COOK'S STOVE.

The Schedule referred to in these Letters Patent and making part of the same.

To all whom it may concern:

Be it known that I, ISAAC N. ROSS, of Holden, in the county of Worcester, and State of Massachusetts, have invented a new Design for the Plates of a Cooking-Stove; and I do hereby declare the following to be a full, clear, and exact description of the same, reference being had to the accompanying drawings, in which the figure represents, in perspective, a cook-stove, constructed in accordance with my "design."

This stove belongs to that class of cook-stoves known as "square," or "low-oven" stoves.

The top is plain, and the doors are of the usual number and location.

Upon the centre of each door is embossed an elliptical shield, provided with two rows of circular bosses

near its edge, the inner row being smaller than the outer row. At each corner of the panel of the door is a heart-shaped boss, and upon the larger oven-door said corner-bosses are connected by a row of elliptical bosses.

The fuel-door is supported upon a moulded bracket. The corners of the stove are panelled, and the whole is supported upon four ornamented legs.

What I claim as my invention, is—

The design for stove-castings, herein set forth.

ISAAC N. ROSS.
